UNITED STATES PATENT OFFICE

ALBERT H. SHILLMAN, OF BALTIMORE, MARYLAND

ART NEEDLE WORK

Application filed July 12, 1932. Serial No. 622,077.

This invention relates generally to art needlework and more particularly to improvements in the design, arrangement and application of the pattern upon the material 5 to be embroidered.

While this particular invention is primarily adapted for use in connection with such stamped goods as pillow cases and the like, it will be understood that it is not limited in its application solely to pillow tubing or cases but may be employed in all stamped goods having overlying panels wherein one end of one of said panels projects beyond the corresponding end of the other panel 15 and wherein both of said ends are intended to be embroidered. The invention, however, is particularly applicable to pillow tubing, pillow cases and the like wherein the open ends are provided with scalloped edges, one 20 of which scalloped edges extends beyond the other.

Heretofore and prior to this invention stamped pillow cases or bolster tubes have been supplied having scalloped edges adjacent which the design to be embroidered has been stamped. It is among the objects of this invention to provide such pillow tubings or pillow cases wherein the upper panel is of less length than the lower panel so that 25 the free edges of the latter projects beyond that of the upper panel, thus exposing to view the embroidery work appearing on both panels. In order to facilitate the application of the stamped designs to edges of such pillow cases, it has been necessary to trim the scalloped edge of the upper panel to thereby expose the surface immediately within the scalloped edge of the bottom panel, the 30 design to be embroidered being then stamped upon the surface so exposed. This has proved to be a relatively expensive and time consuming method of preparing this class of stamped goods because of the labor and care required in preliminarily trimming the edge of one panel in order to facilitate the stamping of the second panel and it is this 35 expense and time consuming labor which it is among the objects of the present invention to avoid.

More specifically, it is among the objects

of the present invention to provide a pillow case or bolster tube the open end of which is not preliminarily cut to the desired configuration, such as is ordinarily done to provide a scalloped edge, but instead is cut to provide a straight edge, the top panel being provided with a stamped design well removed from said straight edge and the bottom panel being also provided with a corresponding stamped design less removed from 55 said straight edge in consequence of which the design in the top panel is offset relatively with respect to that of the bottom panel. In addition to the foregoing, the designs are stamped upon opposite surfaces of the bolster tube in such manner as to entirely obviate the necessity of separating the top and bottom panels for the purpose of applying the design to that surface of the bottom panel which is to be embroidered. In other words, it is an object of the invention to so stamp the necessary designs upon opposite outer surfaces of the pillow case that whereas the design in the top panel may be embroidered upon the outer surface thereof, the design in the bottom may be as readily embroidered upon the inner surface thereof. To this end, the design in the bottom panel is stamped sufficiently heavy upon the outer surface 60 thereof for the ink to penetrate the fabric whereby to render the design visible upon the inner surface of the bottom panel, the latter surface being that which is to be embroidered.

Other objects of the invention and advantages thereof resulting from details of construction and economies in manufacture will be apparent more fully hereinafter.

The invention consists substantially in the combination, construction, arrangement and relative location of parts, all as is described in the following specification, as shown in the accompanying drawing, and as finally pointed out in the appended claims. In the said accompanying drawing:—

Figure 1 is a plan view of the top surface of a pillow or bolster tubing the opposite ends of which embody the features of the present invention;

Figure 2 is a plan view of the top surface

of a pillow case only one end of which embodies the features of the present invention, the opposite end thereof being closed in accordance with the usual practice;

5 Figure 3 is a plan view of the bottom surface of a pillow case or tubing showing the open end thereof constructed in accordance with the present invention;

10 Figure 4 is a view showing the upper surface of the stamped portion of the bottom panel of the pillow case or tubing, the upper panel being shown partially cut away to expose to view the stamped design in said bottom panel; and

15 Figure 5 is a view showing the pillow case finished as it appears when the embroidery work is completed thereon.

20 Referring now more particularly to the drawing, reference numeral 10 designates the pillow or bolster tube or case as constructed in accordance with the principles of this invention, it being understood, of course, that such pillow case is provided with a top panel 11 and a bottom panel 12, the longitudinally 25 extending side edges of said panels 11 and 12 being suitably secured together to provide a tube or casing within which the pillow may be slipped. If desired, the pillow case may be woven to provide a circumferentially continuous tube in such manner that the panels 30 11 and 12 are continuations of each other in a transverse or circumferential direction. It will be observed that the opposite ends of the pillow case 10 are cut straight, as at 13, 35 and 14, no attempt being made by the manufacturer to trim such edges to provide a particular edge configuration, such as a scalloped edge. Formed in the upper panel 11 at some distance from the edge 13 thereof is a line of 40 hemstitching 15 of any suitable configuration. In the instance shown, the line of hemstitching is of scalloped formation. Immediately within the scalloped line of hemstitching 15 and following the design thereof is a 45 configured design 16 applied by an inked stamp, this stamped design 16 serving as the outline or guide for subsequent embroidery work. Paralleling the line of hemstitching 15 and arranged immediately to the outside 50 thereof is a stamped line 17 which serves as a guide line for subsequently cutting the panel 11 to provide a scalloped edge therefor.

55 Provided in the bottom panel 12 immediately adjacent the straight edge 13 thereof is a line of hemstitching 18, it being observed that while this line of hemstitching 18 is longitudinally offset from the line of hemstitching 15 in the upper panel, the design of the line of hemstitching 18 is such that it complements 60 and forms a continuation of the line of hemstitching 15. As in the case of the upper panel, the bottom panel 12 is also provided with a stamped design or series of designs 65 19 to complement and match the designs 16 in the upper panel. The stamped designs

19 of the bottom panel are applied to the outer surface thereof in such manner that the ink penetrates the fabric of the panel 12 and is visible upon the inner surface thereof, it being understood, of course, that the embroidery 70 work is to be applied in accordance with the design 19 to the inner surface of the panel 12. Due to the longitudinally offset arrangement of the designs 16 and 19, it will be understood that in the finished pillow case both of the 75 embroidered designs will be readily visible and so enhance the appearance of the pillow case.

80 The penetrating ink employed for the purpose aforesaid is preferably the regular stamping ink used for art needle work designs. A perforated pattern of the particular design desired to be applied to the fabric is placed over the fabric and the ink is spread over the pattern with a spreader in such 85 manner that the ink is forced through the perforations of the pattern and into the fabric. By increasing the amount of ink thus applied to the outer surface of the bottom panel 12, a greater penetration of ink through the 90 fabric will be obtained to thereby assure a distinctly visible design upon the inner surface of the bottom panel 12.

95 As appears in the drawing the stamped pillow case as supplied to the customer is also 100 provided with directions printed upon the surfaces thereof. The directions appearing in the top panel 11 are respectively designated by the reference numerals 20 and 21 and in the bottom panels by the reference numerals 105 22 and 23. It will be observed that as respects the stamped design in the bottom panel 12 the directions are that this panel be embroidered upon the inner or upper surface thereof. As respects the upper panel 11 110 the instructions are that the pillow case be cut along the opposite side creases from the free edge 13 thereof to the cutting line 17 and thence along the latter line to provide the desired scalloped edge in said upper panel 11. When the area designated by the reference numeral 24 is thus cut out it will be seen that the underlying design in the bottom panel 12 will be exposed to thereby facilitate the embroidery work thereon.

115 While the pillow case embodying the present invention has been described with reference to only one end thereof, it will be understood, of course, that the procedure is the same at the opposite end in all those cases 120 where the pillow case is in the form of a bolster tube the opposite ends of which are both open. In the case of the ordinary pillow case, only one end thereof is open and it is in connection with this open end that the invention is concerned.

125 From the foregoing, it will be apparent that there has been provided a pillow case or bolster tube of such design and arrangement as to simplify and render less expensive 130

- the application of stamped designs to the bottom and top panels thereof. By reason of the fact that the stamped designs are applied to opposite outer surfaces of the panels 5 11 and 12 it becomes unnecessary for the manufacturer of the stamped goods to trim the edge of the upper panel to the desired configuration, this operation being left to the ultimate consumer or embroiderer. It will be 10 understood, of course, that this invention is primarily concerned with the stamped goods and the method of stamping the same and is only secondarily concerned with the embroidering and finishing of such goods. In 15 the finished product, if desired, the scalloped edges of the top and bottom panels 11 and 12 may be finished with a crocheted lace of any suitable design in the manner indicated in Figure 5.
- 20 It will be understood, of course, that the invention is susceptible of various changes and modifications from time to time without departing from the real spirit or general principles thereof and it is accordingly intended to claim the same broadly, as well as specifically, as indicated by the appended claims.
- What is claimed as new and useful is:—
1. A new article of manufacture of the character described comprising a pair of superimposed panels the corresponding longitudinal edges of which are united to form a casing for a pillow or the like, the opposite ends of the casing being cut to provide substantially straight edges, said panels being respectively provided with stamped designs adjacent the open end of the casing, the stamped design in one of said panels being longitudinally offset with respect to the 35 corresponding stamped design in the other of said panels.
  2. A new article of manufacture of the character described comprising a pair of superimposed panels the corresponding longitudinal edges of which are united to form a casing for a pillow or the like, said panels being of coextensive length with the corresponding ends thereof cut to provide a straight-edged open-ended casing, said 40 panels being respectively provided with stamped designs adjacent the open end of the casing, the stamped design in one of said panels being longitudinally offset with respect to the corresponding stamped design 45 in the other of said panels, and stamped directions applied to each of the panels of said casing for facilitating the cutting of one of said panels whereby to expose to single view both of said laterally offset stamped 50 designs.
  3. In a pillow case, in combination, top and bottom panels respectively provided with coincident straight edges, the upper panel being provided with a stamped design 55 removed somewhat from the straight edge thereof and the lower panel being provided with a complementally stamped design arranged adjacent its straight edge and longitudinally offset from the design in the top panel, said stamped designs being respectively impressed upon the opposite outer surfaces of said top and bottom panels, the stamped design so applied to the outer surface of the bottom panel being sufficiently heavy to be visible upon the inner surface of said bottom 60 panel.
  4. In a pillow case, in combination, top and bottom panels respectively provided with coincident straight edges, the upper panel being provided with a stamped design 65 removed somewhat from the straight edge thereof and the lower panel being provided with a complementally stamped design arranged adjacent its straight edge and longitudinally offset from the design in the top panel, said stamped designs being respectively impressed upon the opposite outer surfaces of said top and bottom panels, the stamped design so applied to the outer surface of the bottom panel being sufficiently heavy to be visible upon the inner surface of said bottom 70 panel, and a guide line upon the outer surface of said top panel for facilitating the removal of a portion thereof to expose to view the stamped design visible upon the inner surface of the bottom panel.
  5. A method of preparing a pillow case or tubing for subsequent embroidery work thereon which consists in fabricating the pillow case in such manner as to provide the 75 ends of the top and bottom panels thereof with coincident, straight edges, in respectively applying to the opposite outer surfaces of said top and bottom panels stamped designs adapted to be subsequently embroidered, said stamped designs being longitudinally offset relatively to each other, the stamped design so applied to one of said panels being of sufficiently heavy imprint to be visible upon the inner surface of said panel.
  6. A method of preparing a pillow case or tubing for subsequent embroidery work thereon which consists in fabricating the pillow case in such manner as to provide the 80 ends of the top and bottom panels thereof with coincident, straight edges, in respectively applying to the opposite outer surfaces of said top and bottom panels stamped designs adapted to be subsequently embroidered, said stamped designs being longitudinally offset relatively to each other, the stamped design so applied to one of said panels being of sufficiently heavy imprint to be visible upon the inner surface of said panel, and in applying to the other of said 85 panels stamped directions for facilitating the removal of a portion thereof to thereby expose to view the design visible upon the surface of the heavily imprinted panel.
  7. In a pillow case, in combination, top 90 panel

and bottom panels respectively provided adjacent the corresponding ends thereof with longitudinally offset stamped designs, said stamped designs being respectively impressed upon the opposite outer surfaces of said top and bottom panels, the stamped design so applied to the outer surface of the bottom panel being sufficiently heavy to be visible upon the inner surface of said bottom panel.

8. A method of preparing a pillow case or tubing for subsequent embroidery work thereon which consists in respectively applying to the opposite outer surfaces of the top and bottom panels thereof with stamped designs adapted to be subsequently embroidered, said stamped designs being longitudinally offset relatively to each other, the stamped design so applied to one of said panels being of sufficiently heavy imprint to be visible upon the inner surface of said panel.

In testimony whereof, I have hereunto affixed my signature.

ALBERT H. SHILLMAN.
